UNITED STATES PATENT OFFICE.

DAVID ROBERT CLIFTON, OF SOUTH BROKEN HILL, NEW SOUTH WALES, AUSTRALIA.

MEANS FOR SUSPENDING AND VERTICALLY ADJUSTING SPRING-ROLLERS AND THEIR ATTACHED WINDOW-BLINDS.

1,333,010.

Specification of Letters Patent.

Patented Mar. 9, 1920.

Application filed November 27, 1918. Serial No. 264,474.

To all whom it may concern:

Be it known that I, DAVID ROBERT CLIFTON, a subject of the King of Great Britain, residing at No. 323 Eyre street, South 5 Broken Hill, in the State of New South Wales and Commonwealth of Australia, have invented Improved Means for Suspending and Vertically Adjusting Spring-Rollers and their Attached Window-Blinds, 10 of which the following is a specification.

This invention has been designed so as to permit of a spring roller and its attached blind being so suspended as to allow of its being vertically adjusted and retained in

15 any desired position on the window, so as to admit of the top sash of the window, to which my invention is applied, being pulled down in order to ventilate the room in which the said window is situated. The

20 result is that perfect ventilation of the room is secured without any flapping of the blind, while at the same time the occupants of the room are secure from outside observation. A further advantage of my invention is that in the event of the blind flying

25 upward, there is no possibility of jamming, as it can easily be pulled down by a person standing on the floor thus avoiding any possibility of accident through having to stand on a chair or the like. Further when

30 an old blind is required to be replaced by a new one, it and its roller can be pulled down to a convenient height, and the necessary repairs effected with ease.

35 My invention consists of a horizontal roller fitted with a spindle at each end, which spindles are supported in brackets affixed to the top portion of the frame. Pivoted to the inner side of the left hand

40 bracket is a pawl which is free to engage with a ratchet on the spindle at that end of the horizontal roller. At each end of said roller is a drum, each end of each drum being fitted with a circumferential flange.

45 To each drum is attached one end of a tape. The other ends of said tapes are connected to brackets affixed to the ends of the spring roller carrying the blind, which brackets also carry the said spring roller. A cord is

50 attached to the horizontal roller affixed to the window frame. By pulling this cord the tapes before referred to are wound upon or unwound from the drums at the end of said horizontal roller thus raising or lower-

ing the spring roller and its blind to any 55 predetermined position.

Referring to the drawings hereto annexed:—

Figure 1 is an isometric projection showing my invention applied to a window, the 60 spring roller and its blind being lowered to a point about level with the top of the bottom sash.

Fig. 2 is a side elevation of the left hand bracket carrying the horizontal roller at the 65 top of the window frame, showing the pawl pivoted thereto and the ratchet on the spindle of said horizontal roller.

Fig. 3 is a perspective view of one of the brackets which support the spring roller the 70 lower end of one of the tapes which engages with the drums on the horizontal roller being shown connected thereto.

Fig. 4 is a view showing the rivet clip for attaching the lower ends of the tape to 75 the bracket on the spring roller.

1 is a horizontal roller supported by spindles 2 in brackets 3 (one only being shown) affixed to the top of the window frame. 4 are the drums one on either end of said horizontal roller and 5 are the flanges of said drums. 6 is the pawl pivoted to the inside of the left hand bracket 3 not shown in Fig.

1 and 7 is the ratchet on the left hand end of the spindle 2 with which ratchet said 80 pawl is free to engage. 8 is the cord for operating said horizontal roller 1. 9 are the tapes attached at their upper end to the drums 4. 10 is one of the brackets to which the lower ends of said tapes 9 are connected. 90

11 is a slot in the lower portion of said bracket through which the spindle of the spring roller 12 passes; being held thereon by a split pin or other approved means. 13 is the blind attached at its upper end to said 95 spring roller, 14 is a slot in the upper portion of bracket 10 through which the lower ends of the tapes 9 pass and are turned back on themselves and fastened in position by rivet clip 15. 16 is a short horizontal tube 100 attached to each of the brackets 10. These tubes prevent any possibility of the overwinding of the tapes on the drums 4 and at the same time provide means for holding a rod for carrying a fringe or other ornamentation.

I claim:—

Improved means for suspending and ver-

tically adjusting a spring roller and its attached blind, including a pair of brackets secured to the top portion of the window frame, a horizontal roller having spindles at 5 its ends for engagement with the brackets, a ratchet on one of said spindles, a pawl on the bracket adjacent thereto, drums on the ends of said roller, tapes having one of their ends attached to the drums, spring 10 roller receiving and supporting brackets secured to the other ends of the tapes, a cord

having one end attached to the center of the horizontal roller and its inner portion partially wound thereabout for facilitating the operation of the said roller, and horizontal 15 tubular elements carried by the front faces of the spring roller receiving and supporting brackets for serving as stops and being adapted to receive an ornamental supporting rod.

DAVID ROBERT CLIFTON.
